IMPRESSION ROLLER DRIVE

Edward F. Dudley, Oak Park, Ill., assignor to
Miehle Printing Press & Manufacturing Com-
pany, Chicago, Ill., a corporation of Illinois

Application November 17, 1938, Serial No. 240,919

9 Claims. (Cl. 101—268)

This invention pertains to an improvement in driving mechanisms such as are used more particularly on presses of the power plate type which print from engraved plates.

In order to assure the required pressure for producing a satisfactory impression from such plates, it has been common practice heretofore to provide an impression or D-roller, which carries an impression blanket, and a second impression roller of greater diameter than said D-roller and having a plain surface, serving as a counter member during the printing operation.

The impressional forces necessary for printing paper currency, bonds and the like from engraved plates exceed those required in regular gravure printing, and the speed at which the impressions are pulled is comparatively slow. It is evident, therefore, that the printing members, such as the cooperating impression rollers, are subject to considerable stresses and wear.

In power plate presses of a well-known type, the planks which carry the printing plates are supported on tracks and by means of a chain drive they are drawn over said tracks to the various stations where they are being inked in, wiped and printed from.

It has been found that due to the excessive pressure required as explained above, and due to the constant pull applied to the planks by the chain drive at the time when said planks are being drawn between the D-roller and its co-operating impression roller for effecting an impression, the latter roller is urged forward somewhat faster under the action of the plank than its gear would actually drive it. In other words, the driving gear on said roller is being advanced, but only so far as its backlash will permit, resulting in a slight slippage and eventual unequal wear of the roller surface.

One of the principal objects of my invention therefore is to provide an improved roller drive whereby the above referred to condition shall be eliminated.

Another object resides in the provision of means which shall permit rotation of the impression roller independent of its driving means.

Further objects of the invention will be apparent from the following description and appended claims read in conjunction with the accompanying drawings, in which:

Figure 1 is a side elevation seen from the drive side of that part of a power plate press which includes the impression rollers and drive therefor;

Figure 2 is a front elevation of the same part

but viewed from the left of Figure 1, and showing the gear side of said part to the left; and

Figure 3 represents diagrammatically the means whereby the printing plate carrying planks are advanced and drawn between the impression rollers.

According to the preferred embodiment illustrated by way of example, the D-roller 10 and the large impression roller 11 are mounted in upright frame sections 12 and 13 provided in any suitable manner on the press frame 14. The drive shaft 15 has keyed to its inner end a pinion 16 which meshes with the roller gear 17 mounted free for rotation on the journal 18 of the roller 11 so that the latter may be rotated independently of the gear 17. To the end of said journal is keyed a ratchet 19 and the driving gear 17 carries a spring actuated pawl 20 which engages the teeth of said ratchet. With this arrangement it will be seen that if the roller 11 is urged forward somewhat faster under the action of the plank 21 than the gear 17 would normally drive it, then the ratchet 19 will advance perhaps one tooth each time a plank 21 passes over it, consequently the roller 11 will gradually advance during the operation of the press and the wear will become distributed over the entire circumference of the roller.

The D-roller 10 may be driven from the gear 17 through the intermediary of pinions 22 and 23 and the roller gear 24.

As is usual in printing presses of this type, the journal bearings 25 and 26 of the D-roller 10 and roller 11 respectively, are slidably supported within slots 27 and 28 formed in the uprights 12 and 13 and are held against resilient means such as coil springs 29 so that the rollers can be adjusted vertically relative to each other and to the planks 21 in a manner well-known in the art.

Referring now to Figure 3 of the drawings, I have indicated merely diagrammatically the preferred means whereby the planks 21 with the printing plates 30 are advanced over their tracks 31 and between the two impression rollers 10 and 11. For that purpose I provide an endless chain 32 which carries at intervals studs 33 which engage within recesses 34 located in the center of the bottom face of each plank 21. The chain 32 is preferably driven from a main drive gear 35 which meshes with a pinion 36 mounted at the end of a shaft 37 suitably supported in bearings 38. The upper end of the shaft 37 carries a sprocket 39 which engages the chain 32 that is maintained taut at all times in order to elimi-

nate any backlash and to assure a smooth advance of the planks 21. The roller 11 is formed with an annular recess 40 in order to accommodate the traveling chain 32 and studs 33 as they pass over said roller.

It will be understood that while I have illustrated one preferred embodiment of my invention, I desire to cover any such modifications that will come within the terms of the appended 10 claims.

I claim:

1. A printing press of the class set forth, having in combination, a pair of impression rollers, a printing plate supporting plank, arranged 15 to be drawn between said rollers, driving means for said rollers and plank, and one way clutch means associated with the driving means of one of said rollers to permit movement of the latter independent of the driving means for the purpose 20 of eliminating unequal wear of the surface of said latter roller.

2. A printing press of the class set forth, having in combination, a pair of impression rollers, a printing plate supporting plank, arranged to 25 be drawn between said rollers, driving means for said plank, driving means for said rollers comprising a train of gears, and one way clutch means associated with one gear to permit movement of one of said rollers independent of the 30 rotation of said gear for the purpose of eliminating unequal wear of the surface of said latter roller.

3. A printing press of the class set forth, having in combination, an upper impression roller 35 and a lower impression roller, a printing plate supporting plank, arranged to be drawn between said rollers, driving means for said rollers and plank, and one way clutch means associated with the driving means of said lower impression roller 40 to permit movement of the latter independent of the driving means for the purpose of eliminating unequal wear of the surface of said lower impression pressure.

4. A printing press of the class set forth, having in combination, a pair of impression rollers, a printing plate supporting plank, arranged to be 45 drawn between said rollers, driving means for said rollers and plank, and a ratchet and pawl device associated with the driving means of one 50 of said rollers to permit movement of the latter independent of the driving means for the purpose of eliminating unequal wear of the surface of said latter roller.

5. A printing press of the class set forth, having in combination, an upper impression roller 55 and a lower impression roller, a printing plate

supporting plank, arranged to be drawn between said rollers, driving means for said plank, driving means for said rollers comprising a train of gears, and a ratchet and pawl device associated with the driving gear of said lower impression roller 5 to permit movement of the latter roller independent of the rotation of said gear for the purpose of eliminating unequal wear of the surface of said lower impression roller.

6. A printing press of the class set forth, having in combination, an upper impression roller, a lower impression roller, a support for a printing plank, means for moving a plank over said support, and driving means for said rollers including one way clutch means associated with said lower 15 impression roller to permit movement of said roller independent of its driving means for the purpose of eliminating unequal wear of the surface of said latter roller.

7. A printing press of the class set forth, having in combination, an upper impression roller, a lower impression roller, a support for a printing plank, means for moving a plank over said support, and driving means for said rollers including 25 a ratchet and pawl device associated with said lower impression roller to permit movement of said roller independent of its driving means for the purpose of eliminating unequal wear of the surface of said latter roller.

8. A printing press of the class set forth, having in combination, a pair of impression rollers, a printing plate supporting plank, arranged to be drawn between said rollers, driving means for said rollers and plank, a gear mounted for rotation on the shaft of one of said rollers, a ratchet 35 mechanism associated with said gear to provide a positive drive for said roller in one direction and permit movement of said roller in advance of said gear in the same direction for the purpose of eliminating unequal wear of the surface of 40 said latter roller.

9. A printing press of the class set forth, having in combination, an upper impression roller and a lower impression roller, a printing plate supporting plank, arranged to be drawn between 45 said rollers, driving means for said rollers and plank, a gear mounted for rotation on the shaft of said lower impression roller, a ratchet mechanism associated with said gear to provide a positive drive for said roller in one direction and 50 permit movement of said roller in advance of said gear in the same direction for the purpose of eliminating unequal wear of the surface of said latter roller.

EDWARD F. DUDLEY. 55

CERTIFICATE OF CORRECTION.

Patent No. 2,195,243.

March 26, 1940.

EDWARD F. DUDLEY.

It is hereby certified that error appears in the printed specification of the above numbered patent requiring correction as follows: Page 2, first column, line 43, claim 3, for the word "pressure" read --roller--; and that the said Letters Patent should be read with this correction therein that the same may conform to the record of the case in the Patent Office.

Signed and sealed this 14th day of May, A. D. 1940.

(Seal)

Henry Van Arsdale,
Acting Commissioner of Patents.
